E. E. THOMAS

HAND FIRE EXTINGUISHER

Filed April 28, 1926

Inventor

Edwin E Thomas

by J. J. Geisler

Attorney

UNITED STATES PATENT OFFICE.

EDWIN E. THOMAS, OF PORTLAND, OREGON, ASSIGNOR TO JOHN KIERNAN, OF PORTLAND, OREGON.

HAND FIRE EXTINGUISHER.

Application filed April 28, 1926. Serial No. 105,317.

My invention relates to a hand fire extinguisher.

The object of my invention is to provide an efficient hand fire extinguisher of simple 5 and inexpensive construction consisting of few parts, and readily accessible for inspection and cleaning, and such other attentions as may be required.

Furthermore to construct my fire extinguisher so that it requires only a single valve, and so locate this valve that it will not be 10 in the liquid in the container.

Furthermore to provide a fire extinguisher having a container of large interior capacity 15 for the chemical fluid, at the same time, keeping the exterior dimensions of the container to the standard size of hand fire extinguishers.

Furthermore, to provide in an extinguisher of this type a pressure pipe opening 20 at one end into a bore on the outlet side of the controlling valve and extending longitudinally of the pump cylinder and downwardly to and through the head, the pressure 25 pipe being extended substantially in contact with the pump cylinder throughout its full length above the head, so that the pipe may be protected by the cylinder against bending or distortion in the handling of the 30 cylinder.

I attain my object in a hand fire extinguisher comprising an elongated liquid container provided with a removable head at one end of the container and an air pump 35 mounted on and transversely of said head. An air charging tube is arranged lengthwise of the exterior of the air pump, the intake end of said air charging tube extending into and being fixed to the air expelling end of 40 the air pump and at its opposite end entering through and being fixed in said container head. A valve is between the intake end of said air charging tube and the air expelling orifice of said air pump. The 45 outer end of said valve chamber is provided with a removable head to permit access to the said chamber, and a ball is in said valve chamber controlling the latter expelling orifice. A liquid expelling tube is also ar- 50 ranged lengthwise of the exterior of the air pump, having a perpendicular end extending into the bottom of said container and its opposite end terminating in a nozzle, located at the expelling end of said pump.

55 Preferably said perpendicular portion of

the liquid expelling tube is made with a flexible section to insure that its intake end will at all times be immersed in the lowermost portion of the liquid in the container, and furthermore preferably a cap is remov- 60 ably mounted over said expelling orifice.

The details of construction of my invention are illustrated in the accompanying drawings hereinafter fully described:

In the drawings:

Fig. 1 is a plan view of my invention showing one end of the air pump cylinder cut away at its valve controlled expelling end to show the operation of said valve.

Fig. 2 is a sectional side view of my invention illustrating also that that end of the liquid expelling tube immersed in the liquid container has a flexible section thereby to hold by gravity the intake end of this tube in the lowermost portion of the liquid in the 75 container.

Fig. 3 is a fragmentary large scale section of the head end of the liquid container, showing the air charging tube and the liquid expelling tube (by dotted lines), in relation 80 to the hand pump and container.

Fig. 4 is a large scale fragmentary sectional view of the expelling end of the air pump illustrating the arrangement of the air charging and liquid expelling tubes.

My invention comprises a liquid container *a* and a removable cap *b* upon which is mounted at its middle, in a position at right angles to the said container, a pump. A cylinder *c* of the pump contains a piston *d* and a piston rod *e*, and is actuated by the handle *f*. In the bushing at the handle end of the cylinder through which the piston rod *e* moves, is a vent *g*, which provides a means for the air to be drawn into the cylinder.

At the opposite end of the pump cylinder *c* is an elongated valve chamber *i*, provided with a removable head *h* to permit access to the said chamber, and a ball *j* in said chamber to prevent the reverse passage of the air. An orifice *k* in the side of the valve chamber *i* from which an air charging tube *l* extends, lengthwise to and outside the pump cylinder and into the end of the container *a* adjacent to the pump cylinder.

A liquid expelling tube *m* is arranged lengthwise to and on the exterior of said pump cylinder on the opposite side to the air charging tube, and extending into the 110

bottom of the container as at *n*. This tube includes a flexible section *o*. At the expelling orifice *p* is a removable cap *q*, that is fastened to the tube *m* by a guard chain *r*.

5 As the piston *d* travels inward, the air is forced through the valve chamber *i* and into the air charging tube *l*, and into the container where a pressure is created. The ball *j* prevents the reverse passage of the air, 10 and the liquid is forced through the liquid expelling tube *m* and expelled through the orifice *p*. The cap *q* is to prevent the said orifice from becoming clogged when the extinguisher is not in use.

15 The flexible section *o* in the tube *n* is provided so that the end will accommodate itself to any position and be immersed in the liquid.

My invention will have only one valve 20 and few parts, its simplicity of construction reduces the possibility of its failing to function at a critical time. The pressure will force the protective cap off and there are no valves or pet-cocks which an excited, amateur fireman might forget to open. This fire extinguisher is always ready for use and action, it only need be charged with a suitable chemical.

I claim:

30 1. In a liquid fire extinguisher, the combination of liquid container having an open upper end, a removable head for closing said open end, a pump cylinder secured to said head and arranged at right angles to the 35 longitudinal axis of the container, said cylinder projecting at one end beyond said head, a member having a bore fitting in said end of the cylinder and forming a closure therefor, an outwardly opening valve arranged at the inner end of said bore for

controlling communication between the pump cylinder and said bore, removable means to close the outer end of said bore and to facilitate access to said valve, and a pressure pipe opening at one end into 45 said bore on the outlet side of said valve and extending longitudinally of said pump cylinder and being projected downwardly to and through the head, said pressure pipe extending substantially in contact with the 50 pump cylinder throughout its full length above the head, whereby said pipe is protected by the cylinder against bending or distortion in the handling of the extinguisher.

2. A hand fire extinguisher comprising a liquid container, a removable head for closing said container, a pump cylinder carried by the head and arranged at right angles to the axis of said container, said cylinder projecting at its discharge end beyond said head, a plug member closing said discharge end of the pump cylinder and having a passage therethrough, an outwardly opening valve in said passage, a head removably 60 engaging the plug to close the outer end of the passage, a delivery pipe communicating with the passage on the outlet side of the valve and extending longitudinally of and in close proximity to the cylinder and opening through the head of the container, and a liquid delivery tube having an open end arranged within the container and extending through the container head, said tube 65 beyond the container head being extended 70 longitudinally of and in close proximity to the cylinder with the discharge end adjacent the valved end of the cylinder.

EDWIN E. THOMAS.
